INVENTOR
BY Victor J. Evans

ATTORNEY

UNITED STATES PATENT OFFICE.

ROYAL SHERMAN ALCOX, OF AMES, IOWA.

CONDENSER.

Application filed July 28, 1923. Serial No. 654,427.

To all whom it may concern:

Be it known that I, ROYAL S. ALCOX, a citizen of the United States, residing at Ames, in the county of Story and State of Iowa, have invented new and useful Improvements in Condensers, of which the following is a specification.

This invention relates to an electrical condenser or high-potential accumulators and 10 more particularly to a condenser of adjustable capacity of a type suitable for use with electric currents such as is used in radio transmission.

An object of the invention is to provide a 15 condenser as specified, which has a relatively great adjustability and capacity with respect to its size.

Another object of this invention is to provide a condenser in which two electrodes are 20 provided, each of which comprises a plurality of semicircular plates, one set of which is adjustable in a rotary and longitudinal manner with respect to the other set of plates.

25 Other objects of the invention will appear in the following detailed description taken in connection with the accompanying drawings wherein:

Fig. 1 is a side elevation of the improved 30 condenser.

Fig. 2 is a vertical section through the condenser showing the adjustable electrode in one position.

Fig. 3 is a section similar to Fig. 2 showing 35 the adjustable electrode in a different position than that shown in Fig. 2.

Fig. 4 is a horizontal section on the line 4—4 of Fig. 3.

Fig. 5 is a detail horizontal section on the 40 line 5—5 of Fig. 2.

Fig. 6 is a fragmentary section on the line 6—6 of Fig. 4.

Fig. 7 is a horizontal section on the line 7—7 of Fig. 3.

45 Fig. 8 is a detail perspective view of a tube used in the condenser structure.

Fig. 9 is a detail perspective view of a second tube used in the condenser structure.

Fig. 10 is a perspective view of an adjusting nut used in the condenser structure.

Referring more particularly to the drawings, the improved condenser comprises a base 1 of insulating material and a top 2 also of insulating material. The base 1 and 50 top 2 have a substantially cylindrical mem-

ber 3 attached thereto for forming the wall of the condenser containing casing. A substantially semicircular plate or disc 4 is attached in any suitable manner to the inner surface of the base 1 and it has a plurality of semicylindrical up-standing plates 5 rigidly carried thereby which cooperate with the plate 4 in forming the stationary electrode of the condenser.

A second substantially semicircular plate 6 is provided, which has a plurality of substantially semicylindrical transversely extending plates 7 carried thereby. The plates 7 and disc 6 form the adjustable electrode of the condenser. The semicircular disc or plate 6 is carried by a central hub 8 which is in turn carried by a relatively short sleeve 9. The sleeve 9 is slidably mounted about the dial carrying sleeve 10 and it is provided with a pair of diametrically opposed openings 11 adjacent its upper ends which receive therein the diametrically extending pins 12 formed on the nut 13. The nut 13 moves vertically in the sleeve 10 which latter sleeve is provided with longitudinally extending slots 14 in which the pins 12 travel. The nut 13 is threaded upon the threaded stem 15, as clearly shown in Figs. 2 and 3 of the drawings so that upon rotation of the stem 15, through the medium of 55 the knob 16, which is mounted on the stem, the nut 13 and consequently the sleeve 9 and disc 6 will be moved vertically, along the sleeve 10 to adjust the position of the plates 7 longitudinally relative to the plates 5. By 60 particular reference to Figs. 2 and 3 of the drawings, it will be noted that the plates 5 and 7 are disposed staggeredly so as to permit interposing of the plates 7 between the plates 5.

A dial 17 is mounted on the sleeve 10 for rotating the sleeve 10, to rotate the plate 6 and the plates 7 for adjusting their position laterally relative to the stationary plates 5 and therefore, it will be noted, that a condenser of relatively great capacity in proportion to its size may be provided, and also one in which relatively great adjustment is permitted since the capacity of the condenser may be regulated both by the lateral and longitudinal adjustment of the electrode plates 7 relative to the stationary plates 5.

In Figs. 4, 6 and 7 of the drawings the manner of attaching the plates 6 to the plate 110

4, and the plates 7 to the plates 3 is ill-
lustrated, as for instance; tongues 19 which
extend through the plate 4 and are bent over
against the under surface of the plates 4
5 and 6.

A spring 20 is carried by the under sur-
face of the base 1 and engages the ends of
the stem 15 and sleeve 10 to absorb and pre-
vent end thrust.

10 It is, of course, to be understood that the
invention may be constructed in other man-
ners and the parts associated in different
relations and, therefore, I do not desire to
be limited in any manner except as set forth
15 in the claims hereunto appended.

Having thus described my invention what
I claim is:—

1. A condenser including a stationary
electrode embodying a plurality of substan-
20 tially semi-cylindrical plates, an adjustable
electrode embodying a plurality of semi-
cylindrical plates disposed staggeredly with
respect to said stationary plates, a central
sleeve, a second sleeve slidably mounted on
25 the central sleeve, means carried by the stem
and cooperating with said sleeves whereby
upon turning movement of the stem the
second sleeve will be moved longitudinally
on the central sleeve for adjusting the mov-
30 able plates longitudinally and whereby upon
turning movement of the central sleeve, both
sleeves will be rotated simultaneously to im-

part rotative movement to said adjustable
plates.

2. A condenser including a casing, a sta-
tionary disc and a movable disc in opposed
relation within the casing, semicylindrical
35 plates carried by said discs, a central sleeve,
a threaded stem in the sleeve, a sleeve car-
ried by the movable disc and slidably 40
mounted on the central sleeve, a nut on the
stem having sliding engagement with the
central sleeve and connected to the sleeve
on the movable disc whereby to adjust the
movable disc toward and away from the 45
stationary disc upon rotative movement of
the stem and permit simultaneous rotation
of both sleeves.

3. A condenser comprising a stationary
electrode embodying a plurality of semicy-
lindrical plates, an adjustable electrode com-
50 prising a plurality of semicylindrical plates,
means for rotating said adjustable plates
relative to said stationary plates, and means
for moving said adjustable plates longitu-
55 dinally of the stationary plates, said last
named means being free from interference
with said rotating means to permit longi-
tudinal adjustment of the adjustable plates
60 without effecting their position laterally
relative to the stationary plates.

In testimony whereof I affix my signature.

ROYAL SHERMAN ALCOX.
